A. A. Mixer,

Piano Pedal.

NO. 96,137.

Patented Oct. 26, 1869.

UNITED STATES PATENT OFFICE.

A. A. MIXER, OF HAMILTON, OHIO.

IMPROVEMENT IN PEDALS FOR PIANOS, &c.

Specification forming part of Letters Patent No. 96,137, dated October 26, 1869.

To all whom it may concern:

Be it known that I, ALFRED A. MIXER, of Hamilton, in Butler county, in the State of Ohio, have invented a new and useful Improvement in Pedals for Piano-Fortes or other Similar Musical Instruments; and I do hereby declare that the following is a full and exact description thereof, reference being had to the accompanying drawings, and to the letters of reference marked thereon.

Figure 1 represents a front view of the improved pedal as attached to the treadle of a piano. Fig. 2 represents an edge view of the same.

The object of my invention is to provide an adjustable auxiliary pedal which may be readily applied and used by small children when learning to perform upon such instruments of music as the piano-forte or organ.

In the drawings, the letter A denotes an angular metal bar, which may be made of cast metal.

B denotes the loop, which is secured to the lower end of the angle-piece A by means of a screw, a, which will serve as a pivot, upon which the part A may freely turn, as occasion may require. The screw b is employed to secure the pedal to the usual foot-piece or treadle C of the piano or organ. The foot-rest D is at the upper end of the adjustable bar H, which is provided with a slot, through which the set-screw I passes. By means of the set-screw I and the longitudinal slot K, the bar and foot-rest D H may be adjusted to any desired position.

ccare flanges formed upon the piece A, which serve as guides for the adjustable rest and its bar H.

When applied and in use, the parts will oc-

cupy the position in relation to the treadle of the piano represented in Fig. 1, and the foot-rest may be raised and fastened by the set-screw I to any elevation to be reached as a rest for the feet of children of different sizes, to enable them to actuate the treadles of the instrument; but when the performer is a full-sized person, the auxiliary pedal may be moved by the foot laterally moving upon the pivot a, so as to be out of the way of the performer's foot, which will be placed upon the two screw-heads at b a.

From the foregoing description and drawings it will be seen that my improvement in pedals will enable persons of various sizes and ages to actuate the "sounding-treadles" of the piano or organ, and that it will be unnecessary to remove the auxiliary adjustable pedal from the fixed treadle C (which is attached to the instrument) to permit an adult or full-grown person to perform upon the instrument.

Having fully described my invention, what I claim, and desire to secure by Letters Patent, is—

1. An auxiliary adjustable pedal for piano-fortes, organs, &c., constructed and operating substantially as and for the purposes described.

2. The combination of the loop B, angular bar A, and adjustable part D H, applied and used in the manner and for the purpose substantially as described.

In testimony whereof I have hereunto set my hand this 28th day of August, A. D. 1869.

A. A. MIXER.
